UNITED STATES PATENT OFFICE.

GARDNER P. HASTINGS, OF SPRINGFIELD, MISSOURI.

MAGAZINE-FIREARM.

SPECIFICATION forming part of Letters Patent No. 576,964, dated February 9, 1897.

Application filed January 16, 1896. Serial No. 576,719. (No model.)

To all whom it may concern:

Be it known that I, GARDNER P. HASTINGS, of Springfield, in the county of Greene and State of Missouri, have invented a new and 5 useful Improvement in Firearms, of which the following is a full, clear, and exact description.

My invention relates especially to an improvement in repeating or magazine firearms; 10 and the object of the invention is to so construct the arm that it will be simple, durable, and economic in its construction and which shall be capable of being used in a convenient and rapid manner.

15 A further object of the invention is to provide in a magazine-arm a mechanism by means of which the empty shell will be extracted by the loaded shell that is to be next placed in the cartridge-chamber and to provide 20 an extractor operated from the breech-block that will be effective and sure in its action.

25 A further object of the invention is to provide a means whereby a better bearing of the slide action upon the hammer will be obtained than heretofore for cocking the said hammer, and, furthermore, to construct the firing-pin in two sections, one of which is located in the breech-block and is adapted to strike the 30 shell, the other section, which is adapted to receive the impact of the hammer, being placed in a recoil locking-block occupying such position during the extracting of a shell and the loading of the cartridge-chamber as 35 to carry the breech-section of the firing-pin entirely out of the path of the hammer, the breech-section of the firing-pin being brought into concerted action only with the other section when the cartridge is fully within the 40 cartridge-chamber and all parts are in position for firing.

45 A further object of the invention is to provide a magazine which may be expeditiously and conveniently secured to or detached from the gun, and one which may be loaded when the parts of the gun are in firing position.

50 The invention consists in the novel construction and combination of the several parts, as will be hereinafter fully set forth, and pointed out in the claims.

Reference is to be had to the accompanying drawings, forming a part of this specification,

in which similar characters of reference indicate corresponding parts in all the figures.

Figure 1 is a side elevation of the complete 55 gun. Fig. 2 is a longitudinal section taken on an enlarged scale through a portion of the stock and frame and likewise through a portion of the magazine and barrel of the arm, the said section being taken substantially on 60 the line 2 2 of Fig. 4 and the parts of the gun being shown in firing position. Fig. 3 is a section similar to Fig. 2, except that the parts are in the position they occupy when the gun has been fired and a cartridge is in position 65 to be introduced into the cartridge-chamber. Fig. 4 is a horizontal section taken substantially on the line 4 4 of Fig. 2. Fig. 5 is a horizontal section taken substantially on the line 5 5 of Fig. 2. Fig. 6 is a transverse vertical section taken substantially on the line 6 6 of Fig. 2. Fig. 7 is a detail plan view of the forward end of the breech-block, illustrating the application thereto of a clamping device adapted to act in conjunction with the 75 extractor. Fig. 8 is a vertical section taken substantially on the line 8 8 of Fig. 4. Fig. 9 is a section taken substantially on the same plane, the hammer, the firing-pin, and the breech-block having been removed. Fig. 10 is 80 a bottom plan view of the carrier adapted to carry the loaded shells from the magazine to the cartridge-chamber. Fig. 11 is a rear end view of the said carrier. Fig. 12 is a detail view illustrating the manner in which the 85 outer end of the magazine is attached to the barrel; and Fig. 13 is a sectional view, on the line 13 13 of Fig. 3, of the spacing-block adapted to be placed between the barrel and the magazine.

90 In the drawings, A indicates the frame, to one end of which is secured in any way the stock B, and C indicates the barrel, which, with the magazine D, is secured to the other end of the frame, said barrel and magazine 95 having their ends open to the interior of the frame and the barrel C being arranged above the magazine in the usual way.

In the magazine D is arranged a follower 10, actuated by a spring 10^a and arranged to 100 force the cartridges in the magazine toward the frame A, and said follower is made to fit snugly into the magazine, its rear end forming a shoulder 11, adapted to engage an off-

set or projection 12, produced at the end of the magazine next to the frame, so that the follower will be held in the magazine when the latter is detached from the frame. To hold the magazine in place, its end is slotted, as shown in Figs. 2 and 3, to receive a pin or stud 14 at one side of the socket in the frame wherein the end of the magazine fits.

The forward end of the magazine is so attached to the firing-barrel that the magazine may be quickly attached to or detached from the barrel. This is preferably accomplished as shown in Figs. 1 and 12, in which a bolt 15 is passed through the magazine, being held to turn loosely therein; and the upper end of this bolt is threaded and is adapted to enter a socket 16, formed upon the under face of the barrel and correspondingly threaded. The screw 15 has limited endwise movement in the magazine, and is held in position by forming an annular longitudinal groove 16^a at or near the center of the screw, to be engaged by a set-screw or pin 18, passed through the cap 17 of the said magazine. At the lower end of the attaching-screw 15 a handle 19 is formed, extending at an angle to the body of the screw and provided with a head which, when the screw is fully seated within the socket of the barrel, may be sprung into a recess or depression 20 in the bottom portion of the magazine.

The frame A is provided with a chamber E, extending vertically through the front portion of the frame. The top portion of this chamber is normally closed by a slide 21, moving in guides 21^a, formed on the upper side portions of the frame near the rear end of the open top of the chamber, as shown in Figs. 2 and 3, and said slide is actuated by the breech-block, as will be hereinafter set forth. A bottom 22 is provided for the lower portion of the chamber E, and the aforesaid bottom has side flanges 23 and its upper face is preferably concaved. The rear end of the bottom plate 22 is fulcrumed upon a pivot or stud 24, contained in the lower portion of the aforesaid casing-chamber; but the forward end of the said bottom plate is free to move upward and is preferably provided with a transverse rib at the said end, having a concaved upper surface, and the said surface is preferably rounded off.

At the right-hand side of the forward end of the bottom plate 22 an upright cam-face 26 is formed, as shown in Fig. 5, and this cam-face upon the upward movement of the bottom plate engages a shoulder 27, formed upon the inner side of a spring-latch 28, which extends longitudinally within a slot 29, made horizontally in the frame, the rear end of the spring being secured to the outer face of the frame, as is also shown in Fig. 5. The spring-latch is provided with a head 30, which in the normal position of the latch will extend over the inner end of the magazine a sufficient distance to engage with the rim of the inner-

most cartridge 31 in the said magazine, preventing the cartridge from escaping.

When an extraction of an empty cartridge is to be made, the bottom 22 is inclined or carried upward at its forward end, as shown in Fig. 3, its movement in this direction being limited by contact with a stop 22^a, and, as heretofore stated, upon this movement of the bottom plate the spring-latch 28, which I do not claim as my invention, is carried out of engagement with the cartridge; but at this time or when the bottom plate is in this position it is not desirable that the cartridge shall escape into the chamber E, and such an escape is prevented by forming lugs 32 upon the front lower edge of the said bottom plate, which engage with the cartridge and serve as stops therefor when released from the said spring-latch 28, as shown in Figs. 3 and 5.

A transverse partition 33 is located in the chamber E at its central lower portion and preferably in advance of the pivot of the bottom plate, the pivot-point of which plate is ordinarily near the trigger-guard 34. The hammer 35 may be carried to a cocked position by means of an attached trigger 36 and is released by means of a firing-trigger 37, and the hammer, together with the two triggers 36 and 37, may be of any desired construction, the hammer being controlled in its firing movement by the usual mainspring 38, placed under tension when the hammer is in its cocked position.

The hammer is provided with an arm 39 at the outer side of its head, as shown in Fig. 4, and the forward end of this arm enters a longitudinal groove 40, produced in the inner face of the frame, a corresponding and parallel groove 40^a being likewise made in the opposite side of the frame, as is also shown in Fig. 4. The hammer is primarily placed in cocked position by the slide action F, which consists of the sleeve 41 having sliding movement on the magazine and provided with arms 42 at each side, (designated, respectively, as 42 and 42^a), and these arms are carried upward from the said sleeve and thence rearward to the frame, the arm 42 entering the groove 40 and the arm 42^a the groove 40^a in said frame, and in order that such an entrance may be made openings 43 are made in the sides of the frame leading into the grooves 40 and 40^a, the said grooves being closed after the arms of the sleeves 41 are in position in the grooves by means of plates 44, as shown in Figs. 4 and 6. The rear end of the left-hand sliding arm 42 is provided with a downwardly and forwardly beveled surface 45 and a socket or recess 45^a above the said beveled surface, (see Fig. 8,) and when the sliding sleeve has been carried backward to its full extent to effect the extraction of the empty shell and to bring the charged shell in position to enter the barrel the recess 45^a will have received the projection 39 from the hammer 35 and will have carried the said hammer back

to its full-cocked or firing position. It will be observed that under this construction the bearing of the slide action on the hammer is positive and broad.

5 The firing-pin is made in two parts or sections, an exploding-section G to engage the primer of the cartridge and an actuating part or section G' aligned with the section G and actuated by the hammer. The exploding-section G is carried by a breech-block H, mounted for movement longitudinally in the frame with the section G, aligned with the axis of the barrel, while the section G' of the firing-pin is carried in a recoil locking-block 15 H', arranged to move transversely to the path of the breech-block. The locking-block H' serves, when the arm is cocked, to lock the breech-block in place and hold the same against movement under the recoil of the discharge.

The breech-block H comprises a body portion 46, having pins 47 at opposite sides, engaging slots 48, formed longitudinally in the arms 42 and 42^a of the slide action, and provided at its lower and upper parts with rearwardly-extending arms or bars 49 and 50, the lower arm 49 sliding on the top of the partition 33. The arms or bars 49 and 50 are connected at their rear ends by a tie-block 51, 30 forming the back of the breech-block.

At the rear end of the breech-block an opening 52 is made, and at the forward central portion of the breech-block an opening 53 is produced. The exploding-section of the firing-pin has free movement in both of these openings, but is provided with a head 54, or is otherwise enlarged where it passes through the rear of the breech-block; and the said exploding-section of the firing-pin is encircled by a 40 spring 55, having bearing against the shoulder formed by the head 54 and against the body portion of the breech-block, so that when the firing-pin is struck from the rear and forced out beyond the front face of the breech-block 45 into contact with the primer of a cartridge the spring 55 will be placed under tension and will act to return the said section of the firing-pin to its normal position.

The breech-block is preferably provided 50 with a plate 56, secured to its top portion and adapted to strengthen the same, and the said plate is carried rearward a predetermined distance beyond the breech-block; but if in practice it is found desirable the rear extension 55 may be an integral portion of the breech-block. This rear extension, and, in fact, the major portion of the breech-block, is adapted to pass beneath a stirrup K, which is firmly secured within the frame at the rear of the 60 partition 33, extending from the top of the frame downward and comprising a top bar 66, two side bars 67, and a bottom bar 68. - A slot 56^a is made in the frame at the upper portion thereof near the stock and is adapted 65 to receive the upper portion of the breech-block and its rear extension when the breech-block is carried back to admit of the extrac-

tion of a shell; and the slot 56^a is normally covered by a spring cap or cover 56^b, which is secured to the top of the stirrup at one of its ends, being free at the other, so that when the breech-block is carried back the spring-cap will be pressed upward, as shown in Fig. 3.

An extractor 58 is located at the bottom of the breech-block and comprises a spring-shank secured at one of its ends to the breech-block and a hook-like head 59, which projects beyond the front of the breech-block in position to enter a recess 60 in the bottom of the barrel and arranged to engage behind the rim of the cartridge, as illustrated in Fig. 2.

In order to hold the cartridge-shell from slipping out of engagement with the extractor-hook 59 on the breech-block in the rearward movement of the latter, I provide 85 a clamp, as shown best in Figs. 2 and 7. A slot 61 is made in the upper portion of the body portion of the breech-block, and in this slot a lever 62 is fulcrumed at its center, being provided with a head 63 at its outer end 90 to engage with an offset 64 at the front end of the frame, and thereby force the head 65, at the opposite end of the lever, forward and over the cartridge to a clamping engagement therewith, so that the cartridge is held to the 95 breech-block between the clamp and the extractor, and when the breech-block has been moved to its full rear position the head 63 of the clamp, by engagement with the upper bar of the stirrup K, will cause the clamping-head 65 of the lever to be removed from engagement with the cartridge-rim, thereby permitting the cartridge to be thrown upward and out of the chamber E by the ascending filled cartridge, as will be hereinafter set 105 forth.

The slide 21 is attached to the breech-block by means of a screw 57 or its equivalent, and consequently the forward portion of the chamber E will be fully open at the top when the breech-block is in its retracted position. The locking-block H', carrying the actuating-section G' of the firing-pin, consists of a head 69, adapted to have movement between the rear end of the breech-block H and the forward face of the stirrup K, and likewise between the stirrup and the back face of the partition 33 and a sleeve 70, which extends rearwardly and has guided movement between the vertical members of the stirrup, and the body of the actuating-section of the firing-pin rests in this sleeve and in an opening made in the head, the opening being so located that when the locking-block is in position behind the breech-block and the hammer strikes the actuating-section of the pin it will engage and drive forward the exploding-section by contacting therewith.

The head of the locking-block is provided with a yoke 71, located below the sleeve 70, which latter is slotted longitudinally in its under side to permit the passage through it of a depending lug 73 on the section G' of the firing-pin, which lug engages and plays in the

opening in the yoke and forms a stop to guide and limit the movement of said section. The rear end of the section G' of the firing-pin is provided with a lateral arm 72, arranged in the plane of the hammer 35 and adapted to be engaged by the same when the trigger is operated.

Arms 74 are projected from the top of the sleeve 70 over the actuating-section of the firing-pin, and one end of a controlling-arm 75 is passed downward and forward between these upper arms 74 to an engagement with the inner face of the sleeve above the firing-pin section, as shown in both Figs. 2 and 9, and the rear end of this controlling-arm is pivoted to the lug 76 on the inner face of the upper tang of the frame, as is best shown in Fig. 2. The head 77 of a spring 78 has bearing against the under face of the controlling-arm, and this spring is suitably secured at its rear end in the rear portion of the frame.

The locking-block is carried downward out of the path of the breech-block H by the action of the left-hand arm 42 of the sleeve portion of the slide action, and to that end a lever 79 is employed, having a lug 79^a, which engages with the left-hand upper surface of the locking-block, as shown in dotted lines in Fig. 8, and this lever at its forward end is fulcrumed, as shown in Fig. 6, on a pin 80 in the frame below the left-hand slideway 40. The lever 79 lies adjacent to the inner face of the aforesaid arm 42, and as the slide is pushed rearward to retract the breech-block before the arms commence to act on the breech-block by reason of the length of the slots 48 the inclined surface 45 of the inner end of the arm 42 will ride upon a pin 80 on the lever 79 and will press this lever downward, causing it to press the locking-block down against the tension of the spring 78. The further rearward movement of the arms 42 and 42^a will move the breech-block H to its full rear position to admit of the ejection of the cartridge-shell, also permitting the loaded cartridge to be lifted into the path of the breech-block to be carried into the barrel at the return of the breech-block.

As heretofore stated, when the arms 42 and 42^a are pushed far enough rearward to retract the breech-block the arm 42 will carry the hammer to a full-cocked position, and since at this time the locking-block is removed from the path of the hammer, even should the hammer be sprung, the exploding-section of the firing-pin would not be actuated. By providing the head 72 for the actuating-section of the firing-pin a much broader surface is obtained to be acted upon by the striking-face of the hammer.

The cartridges are received from the magazine in a carrier L, located in the chamber E, over the pivoted bottom plate 22 of the same. The carrier is connected with an angular actuating-lever 82, and the said lever passes through the slot formed in the right-hand

member 67 of the stirrup K, as shown in Figs. 2, 3, 8, and 9, being fulcrumed upon the bottom portion of the said stirrup. The longer end 70 of the lever, which extends in front of the partition 33, is provided upon its upper face with a cam or convexed surface 83, adapted for engagement with the breech-block when the same is carried forward to place the loaded shell in position in the barrel.

The carrier L, which is shown in detail in Figs. 10 and 11, in side elevation in Fig. 8, in section in Fig. 2, and in plan view in Fig. 5, comprises jaws 84 and 85, said jaws being 80 pivotally connected and arranged to clamp and hold the cartridge while the same is being lifted into the path of the breech-block. The jaw 85 comprises an upwardly-curved member a and a lower base portion or member a', said members being integral with each other. The member a' of the jaw 85 is recessed at one side to permit the jaw 84, which is pivoted to said member opposite said recess, to play therethrough and engage the 90 cartridge. A spring 88 is secured at its lower end under the jaw 84 and has its free end bent up and arranged to engage the member a of the jaw 85 so as to hold the jaws pressed on the cartridge, and to limit the movement 95 of the jaws on each other I provide the jaw 84 with a projecting stop 89, engaging the under side of the base portion a' of the jaw 85, as shown in Fig. 10. The base portion a' of the jaw 85 is arranged adjacent to the 100 magazine and is adapted to receive the cartridge when forced therefrom, for which purpose its forward edge is curved or bent downwardly to form a lip 90, as clearly shown in the drawings.

The upwardly-extending portion of the jaw 84 is provided near its forward edge with a vertical slot 91, and near its rear edge the said jaw 84 is pivoted to the lever 82 by means of a screw 92 or its equivalent, and a second 110 screw 93 is passed through the slot 91 of the jaw 84 and into the aforesaid lever 82, as shown in Figs. 2 and 3.

A connection is made between the carrier and the pivoted bottom plate 22 of the chamber E by means of a link 94, which is pivoted to the right-hand flange of the said plate, and receives a stud or projection 87, formed on the jaw 85 of the carrier.

On the lower portion of the partition 33 is 120 a lug 95, adapted to support the flanged end of the cartridge when the discharge end thereof is supported in the aforesaid carrier, as illustrated in Fig. 2. The rear end of the lever 82 has an upward inclination and is 125 provided with a pointed rear extremity 96. A pawl 97 is pivoted on the wall of the frame above the pointed end of the said lever, the pawl being notched to receive the said end, and the said pawl is provided with a spring 130 98 to normally hold it in position to lock with the pointed end of the carrier-lever 82 when the two are brought in engagement.

An arm 99 is pivotally connected, prefer-

ably, with the rear end of the carrier-lever, as shown in Figs. 2 and 9, and a spring 100 is secured at one of its ends to the upper end of the arm 99, the said spring being coiled 5 around a stud or other projection 101, made from the rear side of the stirrup K, the opposite end of the spring being secured in the upper tang of the frame.

The operation of the carrier is as follows: 10 When the firing-pin is in position for firing, as shown in Fig. 2, the breech-block having just brought a loaded shell into the barrel, the carrier will have been pressed from the upper position shown in Fig. 3 by reason of 15 the breech-block riding over the upper cam edge 83 of the lever 82, and the carrier when the lever is in its lower position will have been carried downward to such an extent as to engage with its lip 90 the concaved flange 20 25 at the forward end of the bottom plate 22, and the carrier will be carried still farther downward, depressing the plate 22 to its lowest position, as shown in Fig. 2, and the pressure of the lip and the carrier on the flange 25 of the bottom plate will be such as to overcome the influence of the carrier-spring 88 and open its jaws, whereupon the innermost cartridge in the magazine will be pushed by the magazine-follower upon the carrier, the 30 flanged end of the cartridge resting on the lug or support 95, as is also shown in Fig. 2. The hammer may now be tripped and will strike against the projection 72 of the actuating-section of the firing-pin, causing the said 35 section to strike the exploding-section G of the firing-pin and explode the cartridge. The slide action is now operated, the sleeve 41 being slid rearward, whereupon the left-hand arm 42 of the said sleeve, as heretofore stated, 40 will act upon the lever 79 and cause said lever to press downward the locking-block H' prior to the said arms acting upon the breech-block to force the said breech-block rearward. As the breech-block is carried rearward the 45 locking-block continues to descend until it reaches its lowest position in the stirrup K, as shown in Fig. 3, being held in this position by the left-hand arm 42 of the slide action. As the arms 42 and 42^a of the slide action continue 50 their rearward movement, carrying with them the breech-block H, the left-hand arm 42 will engage with the hammer 35 and carry the same to the full-cocked position, and at the time that the breech-block has reached its 55 full rear position the clamping-lever 62 will have struck the top of the stirrup K and will have disconnected the inner or clamping head 65 of the said lever from the flange of the shell of the cartridge drawn from the barrel 60 by the extractor, and at that moment the right-hand arm 42^a of the slide action will have been brought to an engagement with a lug 102, (shown particularly in Figs. 4 and 9,) located on the right-hand side of the pawl 97, 65 and the said pawl will be lifted and the spring 100 will then exert its full tension in a downwardly direction on the rear end of the carrier-

lever 82, forcing the forward end of the said lever upward, which will carry with it the carrier L and the loaded shell in said carrier, causing the loaded shell in the carrier to so forcibly strike the empty shell just extracted from the barrel as to throw the said shell from the chamber E. As the carrier ascends when released from engagement with the bottom plate 75 22 the spring 88 of the carrier will act to draw the jaws together to clamp the loaded shell, and when the bottom plate 22 has reached its full upward movement at its inner end, as shown in Fig. 3, the link 94 will exert such 80 downward tension on the lug 87 of the left-hand or lipped jaw of the carrier as to draw this portion of the jaw downward, firmly locking the jaws in their closed position, since this downward tension on the forward portion of the carrier will prevent the jaws from being forced outward against the tension of the spring 88 by the inertia of the cartridge carried in the carrier. The parts are now in the position shown in Fig. 3 and the carrier 90 will be at a slight elevation beyond the lower face of the barrel. The sleeve 41 of the slide action is then carried outward and carries with it the breech-block H, containing the exploding-section of the firing-pin. The breech-block will then push the shell forward, its extractor will engage the cartridge-rim during this movement, and at just about the time the forward end of the cartridge enters the barrel the breech-block will have engaged 95 with the cam or convexed face 83 of the lever 82 and will force the said lever downward a sufficient distance to relieve the jaws of the carrier from the tension of the link 94. At this time the forward end of the cartridge 100 will be within the barrel, and as the cartridge is further carried forward by the forward movement of the breech-block the lever 82, connected with the carrier, will be proportionately depressed and the jaws of the 105 carrier, upon the downward pressure brought upon the said carrier, will be forced outward against the tension of the carrier-spring 88 and will release the cartridge. In the further forward movement of the breech-block the 110 cartridge will be placed in position in the barrel, the clamping-lever 62, by contact with the projection 64, as shown in Fig. 7, will have its clamping-head forced to a clamping engagement with the upper rim edge of the 115 cartridge, and the loaded cartridge will then be held to the breech-block by the extractor and the clamping-lever. Meanwhile the carrier has been forced downward a sufficient distance to engage with the front concaved 120 flange 25 of the bottom plate 22 and will carry the said plate down to its lower position, and the pressure on the carrier, due to the screw 93 engaging with the lower end of the slot 91 in the right-hand jaw of the carrier, will cause 125 the jaws to open. The carrier-lever will then be held by the breech-block in its lowermost position, as shown in Fig. 2, and the shell from the magazine will be received upon the 130

carrier ready for the next rearward movement of the slide action. When the bottom-plate 22 is raised at its free end, the latch 28, employed to hold the cartridges in the magazine, is forced from engagement with the said cartridges by the cam-surface 27 of the plate engaging with the head of the said latch, and the spurs 32 on the forward lower edge of the bottom plate will at once engage with the innermost cartridge, as shown in Fig. 3, preventing that cartridge from moving into the chamber E, but upon the downward movement of the bottom plate 22 the lugs or spurs 32 will be disengaged from the cartridge slightly in advance of the disengagement-cam of the plate from the latch 28, so that the flange of the innermost loaded cartridge will meet with no obstacle in its passage to the carrier; but the latch 28 will have been released in time enough to engage with the flange of the next cartridge placed in position to be delivered from the magazine, holding it in place until the next extracting and loading operation is to be accomplished.

25 The barrel and magazine are spaced and are prevented from turning by means of a block 110, provided with concaved upper and lower faces and attached to the front of the frame between the sockets receiving the barrel and magazine. When the barrels are in position, they fit snugly to the curved faces of the block.

Having thus described my invention, I claim as new and desire to secure by Letters 35 Patent—

1. In a magazine-firearm, the combination of a frame having a chamber, a magazine and a barrel having a cartridge-chamber adapted for communication with the chamber in the frame, a breech-block having a firing-pin, a hammer, a carrier arranged to move in the chamber of the frame, to carry the cartridges from the magazine to the barrel, the carrier having clamping-jaws to hold the cartridge upon the upward movement of the carrier, a latch to lock the jaws of the carrier when the same is in its uppermost position, and means to actuate the latch to release the carrier-jaws to permit the cartridge to be pushed into the cartridge-chamber, substantially as set forth.

2. In a magazine-firearm, the combination of a frame having a chamber, a magazine and a barrel having a cartridge-chamber adapted for communication with the chamber in the frame, a breech-block having a firing-pin, a hammer, a carrier arranged to move in the chamber of the frame, to carry the cartridges from the magazine to the barrel, the carrier having clamping-jaws to hold the cartridge upon the upward movement of the carrier, a latch to lock the jaws of the carrier when the same is in its uppermost position, and means to release the jaws when the carrier is opposite the magazine and also when the carrier is opposite the barrel, substantially as set forth.

3. In a magazine-firearm, the combination of a frame having a chamber, a magazine and

a barrel having a cartridge-chamber adapted for communication with the chamber in the frame, a breech-block having a firing-pin, means to move the breech-block, a hammer, a carrier arranged to move in the chamber of the frame to carry the cartridges from the magazine to the barrel, the carrier having clamping-jaws to hold the cartridge upon the upward movement of the carrier, means to open the clamping-jaws when the carrier is opposite the magazine, means to move the carrier upward when the breech-block is retracted, whereby the empty shell is ejected, means to lock the jaws of the carrier against opening when the carrier reaches its uppermost position, and means to release the jaws of the carrier when the breech-block is moved toward the barrel, substantially as set forth. 85

4. In a magazine-firearm, the combination of a frame having a chamber, a magazine and a barrel having a cartridge-chamber adapted for communication with the chamber in the frame, a breech-block mounted in the frame to move toward and away from the barrel, a firing-pin, a hammer, a carrier arranged to move in the chamber of the frame to carry the cartridges from the magazine to the barrel, the carrier having clamping-jaws to hold the cartridge upon the upward movement of the carrier, means to open the jaws when the carrier is opposite the magazine, means to move the carrier upward when the breech-block is retracted to eject the empty shell, and means to lock the jaws against movement when the carrier reaches its uppermost position, said breech-block being arranged when moved toward the barrel, to release the carrier-jaws and permit the cartridge to be pushed into the barrel, substantially as set forth. 100

5. In a magazine-firearm, the combination of a frame having a chamber, a magazine and a barrel having a cartridge-chamber adapted for communication with the chamber in the frame, a breech-block arranged to move in the frame toward or from the barrel, a firing-pin, a hammer, a carrier arranged to move in the chamber of the frame to carry the cartridges from the magazine to the barrel, the carrier having clamping-jaws to hold the cartridge, means to open the jaws when the carrier is opposite the magazine, means to move the carrier upward in the chamber in the frame when the breech-block is retracted, said carrier standing when in its uppermost position above the plane of the cartridge-chamber of the barrel, and means to lock the jaws when the carrier is in its uppermost position, said breech-block being arranged when moved toward the barrel to lower the carrier in alignment with the cartridge-chamber in the barrel, and to release the jaws to permit the cartridge to be pushed from the carrier into the cartridge-chamber, substantially as set forth. 125

6. In a magazine-firearm, the combination of a frame having a chamber, a magazine and a barrel having a cartridge-chamber adapted

for communication with the chamber in the frame, a breech-block having a firing-pin, a hammer, a carrier arranged to move in the chamber of the frame to carry the cartridges from the magazine to the barrel, the carrier having clamping-jaws to hold the cartridge upon the upward movement of the carrier, means to move the carrier in the chamber in the frame when the breech-block is retracted, and a stop to be engaged by the carrier when the same is in its uppermost position, to lock the jaws thereof against opening, substantially as set forth.

7. In a magazine-firearm, the combination of a frame having a chamber, a magazine and a barrel having a cartridge-chamber communicating with the chamber in the frame, a breech-block having a firing-pin, a hammer, a carrier arranged to move in the chamber in the frame to carry the cartridges from the magazine to the barrel, and comprising pivotally-connected clamping-jaws to hold the cartridge, means to move the carrier upward in the chamber in the frame when the breech-block is retracted, and a link having a loose connection with one of the jaws of the carrier and arranged when the carrier reaches its uppermost position to lock the jaws thereof against opening, substantially as set forth.

8. In a magazine-firearm, the combination of a frame having a chamber, a magazine and a barrel having a cartridge-chamber adapted for communication with the chamber in the frame, a breech-block having a firing-pin, a hammer, a carrier arranged to move in the chamber of the frame to carry the cartridges from the magazine to the barrel, the carrier having pivotally-connected clamping-jaws to hold the cartridge, means to move the carrier upward in the chamber in the frame when the breech-block is retracted, a pivoted bottom plate for the chamber in the frame, and a link connected to the bottom plate and arranged to engage one of the jaws of the carrier when the carrier is in its uppermost position, to lock said jaws against opening, substantially as set forth.

9. In a magazine-firearm, the combination of a frame having a chamber, a magazine and a barrel having a cartridge-chamber adapted for communication with the chamber in the frame, a breech-block having a firing-pin, a hammer, a carrier arranged to move in the chamber in the frame to carry the cartridges from the magazine to the barrel, a latch to prevent the passage of the cartridges from the magazine to the chamber in the frame, a plate movable on the frame and also adapted to prevent the passage of the cartridges from the magazine to the chamber in the frame, said plate being arranged when actuated to move the latch out of operation, means to move the carrier, and means to actuate said plate when the carrier is moved upward, substantially as set forth.

10. In a magazine-firearm, the combination of a frame having a chamber, a magazine and

a barrel having a cartridge-chamber adapted for communication with the chamber in the frame, a breech-block having a firing-pin, a hammer, a carrier having means to move it in the chamber in the frame to carry the cartridges from the magazine to the barrel, said carrier having clamping-jaws to engage and hold the cartridge when the carrier is moved, and a lug mounted on the frame and projecting into the chamber thereof to support the end of the cartridge when the same is passed from the magazine onto the carrier, substantially as set forth.

11. In a magazine-firearm, the combination of a frame, a barrel, a magazine, a breech-block movable in the frame, a firing-pin, a hammer to actuate the firing-pin, a lever movable in the frame, a carrier connected to the lever and movable in the frame to carry the cartridges from the magazine to the barrel, a dog to lock the lever to hold the carrier normally in position opposite the magazine, means to lift the carrier when released to carry the cartridge in position opposite the barrel, and a slide arranged to actuate the dog to disengage the lever, substantially as set forth.

12. In a magazine-firearm, the combination of a frame, a barrel, a magazine, a breech-block movable in the frame, a firing-pin, a hammer to actuate the firing-pin, a lever movable in the frame, a carrier connected to the lever and movable in the frame to carry the cartridge from the magazine to the barrel, a pivoted dog to lock the lever to hold the carrier normally in position opposite the magazine, a spring to lift the carrier when released to carry the cartridge in position opposite the barrel, and a slide arranged to actuate the dog to disengage the lever, substantially as set forth.

13. In a magazine-firearm, the combination of a frame having a chamber, a magazine and a barrel having a cartridge-chamber adapted for communication with the chamber in the frame, a plate mounted to move in the chamber in the frame and arranged when moved to prevent the passage of cartridges from the magazine to said chamber, a breech-block having a firing-pin, a hammer to actuate the firing-pin, a carrier movable in the chamber in the frame to carry the cartridges from the magazine to the barrel, and a connection between the carrier and said plate, substantially as set forth.

14. In a magazine-firearm, the combination of a frame having a chamber, a magazine and a barrel having a cartridge-chamber adapted for communication with the chamber in the frame, a plate mounted to move in the chamber in the frame and arranged when moved to prevent the passage of cartridges from the magazine to said chamber, a breech-block having a firing-pin, a hammer to actuate the firing-pin, a carrier movable in the chamber in the frame to carry the cartridges from the magazine to the barrel, and comprising pivotally-connected jaws, and a link connecting

the carrier and plate, to actuate the plate from the movement of the carrier and to lock the jaws against opening when the carrier is in its uppermost position, substantially as set forth.

15. In a repeating arm, the combination with the frame, the barrel and the magazine, of a pivoted plate movable to close the magazine, a carrier vertically movable between the magazine and barrel, a link connecting the carrier and the plate, and means for operating the carrier, substantially as described.

16. In a repeating arm, the combination with the frame, the barrel and the magazine, of a pivoted plate movable to close the magazine, a vertically-movable cartridge-carrier, having two jaws embracing the cartridge, a link connecting the carrier with the plate whereby to close the jaws and to swing the plate, and means for operating the carrier, substantially as described.

17. In a repeating arm, the combination with the frame, the barrel and the magazine, of a slide movable longitudinally with the barrel, an arm attached to the slide and running into the frame, a breech-block reciprocated by the arm, an actuated lever within the frame and engaged by the breech-block as the same moves toward the barrel, a cartridge-carrier movable by means of the lever and carrying the cartridges from the magazine to the barrel, a pivoted plate movable to close the magazine, and a link connecting the cartridge-carrier and pivoted plate, substantially as described.

18. In a repeating firing-arm, the combination with the frame, the barrel and the magazine of a longitudinally-sliding breech-block movable in and out of the path of the breech-block locking-block, a cartridge-carrier movable between the magazine and barrel, a pivoted plate movable to close the magazine, a connection between the cartridge-carrier and the pivoted plate, a lever within the frame and connected to the cartridge-carrier, a spring pressing the lever, the lever being engaged by the breech-block as the breech-block moves

forward, whereby to depress the cartridge-carrier, a second lever fulcrumed within the frame and connected with the locking-block, 50 a slide moving longitudinally with the barrel and an arm attached to the slide and reciprocating the breech-block, the arm also engaging the said second lever whereby to actuate the locking-block, substantially as described. 55

19. In a repeating firearm, the combination with the frame, the barrel and the magazine, of a slide running longitudinally with the barrel, an arm attached to the slide and projecting into the frame, a breech-block connected with the arm and longitudinally reciprocated thereby, a locking-block movable in and out of the path of the breech-block, a lever connected to the locking-block and actuated by the arm of the slide, a hammer 65 cocked by the arm of the slide, an exploding firing-pin section carried in the breech-block, an actuating firing-pin section carried in the locking-block, a cartridge-carrier movable between the magazine and the barrel, an actuated lever connected with the cartridge-carrier and engaged by the breech-block when the breech-block moves forwardly whereby to move the cartridge-carrier to the magazine, 75 and a link connecting the carrier and pivoted plate, substantially as described.

20. In a firearm, a hammer with an offset arm, a sliding arm engaging the offset arm to cock the hammer, a longitudinally-sliding 80 breech-block moved by the sliding arm, a sliding locking-block movable in and out of the path of the breech-block, a spring-pressed controlling-arm engaging the locking-block, an actuating firing-pin section carried in the 85 locking-block and having a transverse extension running into the path of the hammer and an exploding firing-pin section carried in the breech-block, substantially as described.
